(57) **CLAIM**

The ornamental design for a modular seating system, as shown and described.

DESCRIPTION

FIG. 1 is a front perspective view of a modular seating system, according to an embodiment of the technology described herein, illustrating the new, original, and ornamental design; FIG. 2 is a front planar view of the modular seating system, illustrating the new, original, and ornamental design; FIG. 3 is a rear planar view of the modular seating system, illustrating the new, original, and ornamental design; FIG. 4 is a top planar view of the modular seating system, illustrating the new, original, and ornamental design; FIG. 5 is a bottom planar view of the modular seating system, illustrating the new, original, and ornamental design; FIG. 6 is a left side planar view of the modular seating system, illustrating the new, original, and ornamental design; FIG. 7 is a right side planar view of the modular seating system, illustrating the new, original, and ornamental design; FIG. 8 is a top perspective view of the modular seating system, according to an embodiment of the technology described herein, illustrating the new, original, and ornamental design; and, FIG. 9 is a top perspective view of the modular seating system, according to an embodiment of the technology described herein, illustrating the new, original, and ornamental design. The broken line shown in the drawings are for illustrative purposes only and form no part of the claimed design.
